Primary Examiner — Marie D. Fast Horse

(57) **CLAIM**

We claim the ornamental design for a smart gateway, as shown and described.

DESCRIPTION

FIG. 1 is a right side view of a smart gateway embodying the invention;

FIG. 2 is a left side view thereof;

FIG. 3 is a top view thereof;

FIG. 4 is a bottom view thereof;

FIG. 5 is a back view thereof;

FIG. 6 is a front view thereof;

FIG. 7 is a perspective view thereof;

FIG. 8 is a right side view of another smart gateway embodying the invention;

FIG. 9 is a left side view thereof;

FIG. 10 is a top view thereof;

FIG. 11 is a bottom view thereof;

FIG. 12 is a back view thereof;

FIG. 13 is a front view thereof;

FIG. 14 is a perspective view thereof;

FIG. 15 is a right side view of another smart gateway embodying the invention;

FIG. 16 is a left side view thereof;

FIG. 17 is a top view thereof;

FIG. 18 is a bottom view thereof;

FIG. 19 is a back view thereof;

FIG. 20 is a front view thereof; and,

FIG. 21 is a perspective view thereof.
